 tion of England

Application May 5, 1936, Serial No. 77,948
 In Great Britain April 27, 1935

9 Claims. (Cl. 90—13.1)

This invention relates to engraving machines embodying a pantograph linkage to control the relative motion of the engraving tool and the work in harmony with the motion of a tracer about a model or copy; and it has for its object to provide improved and more useful constructions of such machines, and particularly to provide:—a more rigid support and control of the cutter; improved means for driving at its end remote from the cutter a rotary cutter spindle carried by the pantograph; improved means by which the plane of the copyholder is brought nearer to the plane of the work; a primary pantograph, preferably fixed, and a secondary pantograph, preferably adjustable, and adapted to work in series with the primary pantograph so as to extend or reduce its range of proportion; means by which, with a pantograph system having a substantial ratio of reduction and a substantial range of motion for the cutter, the copy may be brought near to the work; means by which, with the main axis of the primary pantograph system intermediate between the cutter and the tracer, the copy and the work have the same orientation; improved means by which such a machine may be adapted for engraving in three dimensions from a copy either the same size as, or of a size different from that of, the work; improved cutter-feeding means, and to provide a machine unit comprising a frame adapted to carry a copyholder and a pantograph or pantographs, a rotary cutter spindle and means for driving it, the entire unit being adapted for attachment in alignment interchangeably with various forms of work-holding devices.

I will describe my invention with reference to the accompanying drawings in which:—

Fig. 1 represents in side elevation, and Fig. 2 in plan, an engraving machine embodying the invention. Fig. 3 shows in side elevation, and Fig. 4 in plan, an arrangement of the cutter spindle and its feeding mechanism. Fig. 5 shows, in section, the bearings on one of the principal axes of the primary pantograph. Fig. 6 shows, in plan, a means of attachment of a former-carrying arm. Fig. 7 shows in section, and Fig. 8 in plan, a mechanism for advancing and retracting the tracer in successive predetermined steps.

The machine comprises a base 1 having in its upper surface a longitudinal T-slot 2, beneath it a transverse T-slot 3, and at one end a transverse T-slot 4. Attached by bolts to the T-slot 2 is a copyholder 5 having a tongue 6 which fits the T-slot by which means the copyholder may be ad-

justably set in various positions on the base without changing its orientation. The copyholder includes means such as the series of tapped holes 18 or T-slots, by which a copy or model may be secured to it. By means of the transverse T-slot 5 4, a variety of workholding devices may be attached interchangeably to the base 1, and the said slot being in a plane parallel to the upper face of the base 1, and being at right angles to the T-slot 2, such workholding devices, which are 10 provided with tongues 68, are automatically aligned with the T-slot 2 and thereby with the copyholder 5. The workholder shown is an angle plate 69 with T-slots 70 in its upper face at right angles to the T-slot 2, and by which an object 15 may be secured by means of bolts. Other workholding devices are too well known to need specific description. Similarly, the T-slot 3, which is in a plane parallel to the upper surface of the base 1 and is at right angles to the T-slot 20 2, may be used to attach the machine unit by its base 1 to other forms of workholder such as a column 71, the upper end of which is indicated by dotted lines. Columns of this kind are well known in machine tools, and may comprise vertical guideways 72 on which a slide rest or other workholding device may be mounted for vertical movement. The column is provided with a tongue 73 adapted to engage the T-slot 3 and the base 1, so as to align the machine unit with such 25 elements as the slideway 72 on the column.

Attached to the base is a support 7 with an integral column 8 on a vertical axis which I term the main axis. Mounted on the column 8, on bearings at 9 and 10 spaced well apart, (preferably on ball or roller bearings not shown in detail) is a swivel member 11 which supports, in an axis 12, a pair of bearings 13, 14, spaced well apart. A carriage member 15, carried by said bearings, is adapted to carry in an axis 16 a cutter spindle 19 mounted in bearings in a cylindrical quill 17. The axis 12 (which I term the first axis) is parallel to and in one plane with the main axis at 8, and parallel to and in one plane with the cutter spindle axis 16. As illustrative 45 of what is meant by the expression "spaced well apart" attention is called to the fact that, in the case of the carriage member 15, the effective centres of the bearings for example 13, 14 are at a distance from one another at least equal 50 to the distance between the axes 12 and 16, and similarly, in the case of the swivel member 11, that the corresponding distance between the centres of the bearings on the column 8 is at least equal to the distance between the axes 8 55

and 12. The importance of such proportions is that they go to secure rigid support and control of the cutter spindle 19. As obviously a single long bearing is the equivalent of two bearings spaced well apart, and the latter acting together, in effect, constitute a long bearing, the term "long bearing" is used in the claims to imply either a single long bearing or two separate spaced bearings.

10 The swivel member 11 carries in an axis 20, at a substantial distance from one another, a pair of bearings whereon an arm 21 is pivotally supported, and the axes 21 and 12 are all in one plane parallel to one another. The arm 21 carries in an axis at 22, interchangeably, either a joint pin 23 or a tracer 24, and in an axis 25 is pivotally connected to a link 26, the axes 25, 20 and 22 being all in one plane and parallel to one another. The link 26 is pivotally connected at 27 to a lug 28 on the lower end of the carriage member 15, the axes 27, 16 and 12 of the carriage member being all in one plane and parallel to one another. The distances between the axes 25 and 27, and between the axes 12 and 20, are equal, and similarly, those between the axes 20 and 25, and the axes 12 and 27, are equal. The axes 16, 8 and 22 are arranged in one plane and remain in one plane in all working positions of the members which thus constitute a pantograph.

In the example illustrated, the ratio of the pantograph is fixed at 4 to 1, but may be adjustable in known manner, for example by moving the axis 8 further from 12, and by moving the axis 22 nearer to 20. It is, of course, not essential but it is convenient that the link 26 is placed on that side of the swivel member 11 remote from the tracer axis 22. Means such as a pulley 29 at the upper end of the cutter spindle 19 are provided for driving the spindle by any convenient means which may, for example, include a pulley 30 attached to an electro motor, a belt 31, the motor being desirably carried from the swivel member 11 with its axis in the axis 12 of the carriage member, so that the tightness of the belt is unaffected by the motion of the pantograph. The quill 17 is slidably mounted for longitudinal motion in the carriage member 15, and may be fed downwards so that a cutter 16 carried in the lower end of the spindle 19 may be fed into the object to be engraved or withdrawn therefrom by the following means:—A crosshead 32 fixed to the quill 17 is urged upwards by springs 33, 34 against collars 34, 34 on rods 35, 35, around which the springs are placed and which are fixed in a second crosshead 36. Lugs 37, 38 on the carriage member 15 are drilled to receive one of the rods 35 so as to prevent rotation of the crosshead 36 round the axis 16 of the cutter spindle.

The crosshead 36 has a downwardly projecting tubular sleeve 39 passing through a hole in the lug 37, and mounted rotatably within said hole is a tube 40 with a flange 41, by which it may be manually turned. The tube 40 has a longitudinal internal keyway 42. Mounted rotatably on the crosshead 36 in the axis of the cutter spindle 19 is a nut 43 which may be turned by hand and which, to facilitate such turning, contains a ball-thrust bearing 44, and mounted within the nut is a screw 45 having at its lower end a head 46 from which a key 47 projects radially and, according to the rotational position of the flange 41, either abuts beneath said tube or is free to move into the keyway 42. In order to use

the feed nut 43 to move the cutter spindle 19 up or down, the tube 40 is turned so that the key 47 abuts against its under-side, being urged thereto by the springs 33, 33 which tend to lift the crosshead 36 and the nut 43 and thus to put the screw 45 in tension, the screw 45 being then, in effect, anchored to the lug 37 of the carriage member 15. Turning the feed-nut 43 moves the crosshead 36, the quill 17 and the spindle 19 up or down in relation to the carriage member 15. The nut 43 may be graduated and a fiducial mark provided on the crosshead 36 so that the feeding movement of the quill 17 may be measured.

In order that, when required, the object may be engraved in three dimensions by giving to the cutter spindle 19 an up-and-down motion controlled by a former and follower, the column 8 may be extended upwards so as to carry an arm 48 adapted to support, above the cutter spindle, a former such as 49 of any desired form, the counterpart of that to be formed on the object. The arm may be aligned with the column 8 by means of a seating 50 against which the arm bears on the column, a claw 51 and a wedge-bolt 52 which definitely locate the arm on the column but permit its longitudinal adjustment thereon. The arm may be provided with a tongue 53 adapted to fit in a groove in the former 49, and by these means the orientation of the former may be fixed in relation to the workholding device. Attached to the upper end of the feed screw 45 is a follower 54 which, as shown, has a hemispherical form but may have any convenient form, and this follower is caused to follow the contours of the former 49 and thereby to control the up-and-down motion of the spindle 19 by the following means:—The flange 41 is turned so that the key 47 on the head 46 of the feed screw 45 is free to enter the longitudinal keyway 42 in the tube 40. A spring 55 housed within the tubular sleeve 39 of the crosshead 36 urges the feed screw 45 downwards so as to keep the feed nut 43 seated against the crosshead. The entire unit, comprising the spindle 19, its quill 17, the crossheads 32 and 36, and the follower 54, are then lifted automatically by the springs 33, 33 so that the follower follows the surface of the former 49; but the feed nut 43 may be used to adjustably advance or retract the cutter spindle 19 relatively to the follower 54 so as to adjust the depth of cutting in the object.

In order to reduce the friction between the tubular sleeve 39 and its bearing in the lug 37, due to lateral pressure on the follower 54 when it is operating on a steeply inclined surface on the former 49, a number of balls 56 loosely housed in a cylindrical cage 57 are accommodated in an annular space between the cylindrical exterior of the sleeve 39 and the cylindrical interior of the tube 40, so as to form therebetween a roller bearing for longitudinal motion.

An alternative means of engraving in three dimensions is provided by the following:—The tube 40 is turned in the lug 37 so that the key 47 of the feed screw 45 abuts against the under-side of the flange 41. A peripheral edge of the feed nut 43 is provided with a number of equidistant notches 58 adapted to be engaged by the end of a spring bolt 59 so that, by turning the feed nut for example one notch at a time, the cutter spindle 19 may be advanced or retracted in the carriage member 15 by successive equal amounts, depending on the pitch of the screw 45 and the number of notches 58.

Mounted interchangeably in place of the joint pin 23, the tracer 24 shown in Fig. 7 is placed, the tracer being screw-threaded to engage a hole tapped in a plate 60 which is removably attached 5 to the pantograph arm 21. The tracer 24 has on its lower end a follower 61 which, as shown, has hemispherical form but may have any convenient form preferably corresponding to that of the cutter; and the upper end of the tracer 24 is 10 provided with a head 62 having in its peripheral edge a number of equidistant notches 63 adapted to be engaged by the spring plunger 64 carried by an arm from the lug 60. The pitch of the screw on the tracer and the number of notches 15 63 in the head 62 are so correlated with those of the cutter feed-nut 43 that, by turning both the feed nut 43 and the tracer screw head 62, one notch at a time, the tracer is moved longitudinally an amount, greater than the corresponding 20 movement of the cutter spindle, in the ratio of reduction at which the primary pantograph operates. By these means an object such as a mould may be engraved in three dimensions by fixing on the copyholder 5 a model of the engraving to be produced, enlarged in the ratio 25 at which the pantograph operates, and the engraving is done by taking a series of cuts in parallel planes distant from one another, as determined by the successive advances of the feed screw 45, and in each plane the follower 61 is traversed in a corresponding plane along the contours of the model in that plane.

It is convenient, when using the machine to engrave for example lettering from a copy consisting of engraved lines, that the pantograph arm 21 should be free for small elastic motion in the plane including the axes 20 and 22, and for this purpose the arm 21 is made sufficiently thin and flexible, as seen in the elevation Fig. 1, 30 but broad, as seen in the plan Fig. 2; but when engraving in three dimensions in the above manner, it is desirable that the arm should be rigidly held against such elastic motion, and for this purpose a tie-rod 65, attached to the arm 21 toward its free end, is slidably housed in a hole 66 toward the top bearing which joins the arm 21 to the swivel member 11, and may be locked therein by the eye-bolt 67 so as to resist elastic bending of the arm 21.

50 In an engraving machine having a considerable ratio of reduction, that is, a considerable ratio of the distance between the axis 22 and the axis 8, in Fig. 2, to the distance from the axis 8 to the cutter axis 16, and especially where it is desired to have a considerable range of motion for the cutter 16, the tracer 22 is so remote from the object to be engraved that it is difficult to see, and sometimes difficult even to reach, the tracer and the cutter feed mechanism at the same time. In one 55 type of engraving machine described by me, I encountered the difficulty of supporting the cutter spindle in a carriage member such as 15, pivotally supported in turn on a swivel member which in turn was pivotally supported as on the axis 8 from the machine base, and I mounted a complete and independent pantograph of thin links above the carriage member 15 and connected thereto in the axis of the cutter spindle at 16. This, while making it possible to bring the main 60 axis of the pantograph near to the axis 16 without physical interference, placed the pantograph at a considerable elevation above the surface of the object where it was at a disadvantage in rigidly controlling the movement of the cutter at the lower end of the carriage member. It

also made it difficult to drive the cutter spindle from its upper end, and difficult to attach the follower 54 near to, and in the axis of, the cutter spindle.

By the present invention these difficulties are overcome. The pantograph arm 21 may be placed low down on the swivel member 11 and relatively near to the plane in which the cutter operates. The spindle 19 is free to be driven at its upper end, and there is no pantograph to intervene and to require lateral space between the spindle and the follower 54; but the pantograph cannot have a large ratio of reduction and a large range of motion for the cutter, and it would necessitate, as hitherto, sacrificing the massiveness and rigidity of the swivel member, the carriage member 15, the spindle bearings and the supporting bearings on the main axis 8. Therefore, according to this invention, I embody the carriage and swivel members in a pantograph linkage having only a moderate ratio of reduction, and I use a second pantograph, which I term the secondary pantograph, placed tandem or in series with the primary pantograph, and arranged so that it either increases or reduces the ratio of the primary pantograph. A form of such secondary pantograph is shown in Figs. 1 and 2, in which a bracket 74, bolted to the base by the T-slot 2, carries in bearings 75, 76 on an axis 77, which is the main axis of the secondary pantograph, a supporting link 78 at the ends of which, on axes 79 and 80 respectively, are pivoted two bars 81, 82 adapted to receive sliders 83, 84. The sliders are pivotally connected at 85, 86 to a cross-link 87 adapted to receive a slider 88 which can be pivoted by the joint pin in the axis 22 to the arm 21. In the axis 89 a tracer or follower 90 is carried above the copyholder 5. The links 78, 81, 82 and 87 form a pantograph linkage in which the axes 77, 22 and 89 are at all times 40 in one plane and parallel to one another, and the ratio of the distances between the axes 77 and 89, and 77 and 22, may be varied by adjustably moving the sliders 83, 84 and 88 along their respective bars or links.

Although I have shown a secondary pantograph adapted for reduction, it will be readily understood that, by transposing its long and short arms, pivoting the long arm by its point 89 to the free end 22 of the primary pantograph arm 21, 50 pivoting the slider 86 to the bracket 74 fixed on the base, and putting the style in the axis 88 of the bar 78, such a pantograph would be adapted for enlargement and might, in effect, reduce the ratio of the primary pantograph to zero.

It is an advantage, in pantograph engraving machines, to have the main axis 8 intermediate between the tracer axis 22 and the cutter axis 16 so that the cutter may overhang the frame of the machine to enable the machine to accommodate large objects, but this arrangement entails the disadvantage that, in using the primary pantograph alone, the copy must be placed in the position reversed with respect to the object to be engraved, for example a copy letter would be placed upsidedown in order to engrave the letter right way up. By the use of a secondary pantograph, however, according to this invention, but by moving the supporting link 78 to the other side of the link 87, as shown by the dotted lines in Fig. 2, so that the fixed axis 77 by which the secondary pantograph is supported is intermediate between the axis of the tracer 89 and the axis 22 by which the secondary pantograph is connected to the arm 21 of the primary pantograph- 75

graph, such reversal of orientation of the copy and object is corrected and both have the same orientation.

By arranging the secondary pantograph so that its tracer in the axis 89 is intermediate between the axes 8 and 22 of the primary pantograph, the copyholder 5 is brought relatively near to the cutter spindle 19 notwithstanding that the combined ratio of the pantographs may be a large one.

For convenience, the term "tracer" is used in the claims as indicating not only the tracer 90 of the secondary pantograph but also that point of the primary pantograph at which the tracer 15 would be attached if there was no secondary pantograph coupled thereto. Similarly, the term "cutter" is used to indicate that point of the secondary pantograph at which the cutter would be attached if there was no primary pantograph.

20 In pantograph engraving machines in which hitherto the pantograph has been mounted above the swivel and carriage members supporting the cutter spindle, it has been necessary to drive the cutter spindle by means of a pulley fixed at the 25 lower end thereof, and to employ elaborate devices of guide pulleys with stay rods to lead a driving belt to the cutter spindle pulley and to accommodate the lateral motion of the cutter spindle without changing the tension of the belt.

30 By means of the present invention, which enables me to drive the spindle from its upper end, it becomes practicable to mount an electro motor on the swivel member 11 with its axis in line with the pivot axis 12 of the carriage member, and, 35 from a pulley on the motor spindle, to drive directly the cutter spindle pulley 29.

What is claimed is:

1. In an engraving machine and the like, a primary pantograph linkage comprising an arm 40 and a junction pivot carried thereby, a support, a swivel member pivotally mounted on said support on bearings spaced well apart, and pivotally carrying said arm, a carriage member pivotally carried by the swivel member on bearings 45 spaced well apart and carrying a rotary cutter spindle, and a link connecting the carriage member and the arm, the axes of the junction pivot, the support and the cutter spindle being at all times parallel to one another and in one plane, 50 and a secondary pantograph comprising an arm and a tracer carried thereby, a swivel member pivotally mounted on a support and pivotally carrying said arm, a junction member pivotally joined to the swivel member and pivotally connected by the junction pivot to the primary pantograph, and a link connecting the junction member and the arm, the axes of the junction pivot, the support and the tracer being at all times parallel to one another and in one plane. 55

60 2. In an engraving machine having primary and secondary pantographs as claimed in claim 1, arranging said pantographs so that the orbit of motion of the tracer of the secondary pantograph is nearer to the cutter spindle axis than is the orbit of the junction pivot between the two pantographs.

3. In an engraving machine and the like, a pantograph linkage comprising an arm and a tracer carried thereby, a support, a swivel member pivotally mounted on said support on bear-

ings spaced well apart, and pivotally carrying said arm, a carriage member pivotally carried by the swivel member on bearings spaced well apart and carrying a rotary cutter spindle, and a link connecting the carriage member and the arm, the arm being restrained from motion in any axial plane of a common pivot of the arm and the swivel member, and the tracer and the cutter spindle being adapted for longitudinal movement in the arm and the carriage member 10 respectively, and having means such as screws to move them and means such as catch discs by which they may be moved in successive increments corresponding to the ratio of the pantograph.

4. In an engraving machine, a fixed support, a frame mounted on said support to swing about a fixed axis, a second frame mounted on the first frame to swing about an axis parallel to the first axis, a cutter spindle rotatably mounted on the 20 second frame for rotation about an axis parallel to the other axes, the bearings of the first frame with respect to the fixed support and of the second frame with respect to both the first frame and cutter spindle all being long, whereby the 25 axis of the latter is maintained in exact parallelism with respect to the first axis, a primary pantograph for controlling the lateral movements of the cutter spindle and the supporting means therefor, and a secondary pantograph connected 30 to the primary pantograph for varying the reduction ratio of the first pantograph.

5. An engraving machine as in claim 4, in which the two frames form parts of two links of the primary pantograph, the first mentioned axis being the fixed axis of such pantograph.

6. In an engraving machine, a cutter, a primary pantograph for controlling the lateral movements of said cutter, a fixed pivot therefor, said pantograph having said pivot in the middle 40 of the series, cutter—pivot—tracer, and a secondary pantograph wholly on the tracer side of the fixed pivot of said primary pantograph and having its cutter connected to the tracer of the primary pantograph.

7. In an engraving machine, a cutter, a primary pantograph for controlling the lateral movements of said cutter, a fixed pivot therefor, said pantograph having said pivot in the middle of the series, cutter—pivot—tracer, and a secondary 50 pantograph having its cutter connected to the tracer of the primary pantograph and its tracer between the fixed pivots of the two pantographs.

8. In an engraving machine, a cutter, a primary pantograph for controlling the lateral 55 movements of said cutter, a secondary pantograph having its cutter connected to the tracer of the primary pantograph and the tracer of the secondary pantograph intermediate the fixed pivots of the two pantographs.

9. In an engraving machine, a cutter, a primary pantograph for controlling the lateral movements of said cutter, a fixed pivot therefor, said pantograph having said pivot in the middle of the series, cutter—pivot—tracer, and a secondary 65 pantograph having its fixed pivot in the middle of the series, cutter—pivot—tracer, and having its cutter connected to the tracer of the primary pantograph.
